[57] **CLAIM**

The ornamental design for a helmet for forest fires and catastrophes, as shown and described.

DESCRIPTION

FIG. 1 is a top, front and side perspective view of a helmet for forest fires and catastrophes showing my new design, with the goggles in a raised position;

FIG. 2 is a front elevational view thereof;

FIG. 3 is a right side elevational view thereof, the left side being a mirror image;

FIG. 4 is a rear elevational view thereof;

FIG. 5 is a top plan view thereof;

FIG. 6 is a bottom view thereof;

FIG. 7 is a perspective view thereof, with the goggles in a lowered position;

FIG. 8 is a front elevational view thereof;

FIG. 9 is a right side elevational view thereof, the left side being a mirror image; and,

FIG. 10 is a top plan view thereof.

The unfinished diamond shaped pattern shown in FIG. 6 is understood to repeat throughout the indicated area.
